POCKET LIGHTER

William E. Evans, Waterbury, Conn., assignor to
 The Waterbury Lock and Specialty Company,
 Milford, Conn., a corporation of Connecticut

Application March 17, 1938, Serial No. 196,337

3 Claims. (Cl. 67—7.1)

This invention relates to an improvement in pocket lighters, and particularly to that type in which the movement of the snuffer operates to create a spark to ignite the wick.

5 The object of the invention is to connect the operating-lever with the snuffer so that a comparatively slight movement of the operating-lever will raise the snuffer to its full open position, and upon the release of the lever the snuffer 10 will be returned to its fully-closed position. The invention resides in the construction as herein-after described and particularly recited in the claims.

In the accompanying drawing, in which certain modes of carrying out the present invention are shown for illustrative purposes:

Fig. 1 is a face view of a pocket lighter constructed in accordance with my invention;

Fig. 2 is an edge view of the same;

20 Fig. 3 is a plan view with the front plate removed, with the parts in a closed position;

Fig. 4 is a similar view showing the movable parts in an open position;

Fig. 5 is a sectional view on line 5—5 of Fig. 3;

25 Fig. 6 is a perspective view of the operating-lever detached;

Fig. 7 is a perspective view of the connecting-link detached; and

30 Fig. 8 is a perspective view of the snuffer detached.

In carrying out my invention, I employ a back 10 and a face 11, which together form a casing. Mounted in back is the usual wick-chamber 12 from which a wick 13 projects from the upper end and which may be filled with burning fluid in the usual manner. Adjacent to the chamber is a tube 14 which contains a spring 15 which holds a flint 16 against a sparking-wheel 17. This sparking-wheel is mounted on a rivet 18 extending between the back and face, and upon which pivot the snuffer 19 is also mounted. The snuffer has the usual cup 20 which in the closed position sets over the exposed end of the wick 13 and extinguishes it if lighted. Between the 40 sparking-wheel 17 and the inner side of the snuffer is a sheet-metal spring 21 having a finger 22 adapted to engage with one of several shoulders 23 on the rear of the sparking-wheel 17 so that when the snuffer is raised, the sparking-wheel will be turned to rub upon the flint and produce a spark to ignite the wick. When the snuffer is turned to its closed position, the wheel will ride over the spring without obstruction.

45 The operating-lever 24 is pivotally mounted

5 in the case and closes an opening formed in the side thereof. Pivotally mounted in the lever is a channel-shaped toggle-link 25 projecting into the case and having its inner end set over a post 26 mounted on a connecting link 27 which, in turn, is mounted on a post 28 below the toggle-link 25, and mounted on a pin 29 at the inner end of the connecting-link is an actuating link 30, the opposite end of which is pivotally connected to the inner end of the snuffer. A wire 10 spring 31 is mounted on the post 28, one end extending into engagement with the rivet 32 on which the lever 24 is mounted, and the other end bearing upon the pin 29, tending to lift the outer end of the connecting-link 27 so as to tend to 15 return the operating-lever 24 to its closed position and, at the same time, force the actuating link 30 upward so as to close and hold the snuffer in its closed position.

The invention may be carried out in other specific ways than those herein set forth without departing from the spirit and essential characteristics of the invention, and the present embodiments are, therefore, to be considered in all respects as illustrative and not restrictive, and 20 all changes coming within the meaning and equivalency range of the appended claims are 25 intended to be embraced therein.

I claim:

1. A lighter comprising in combination: a 30 casing, a wick, a flint, a sparking-wheel, a snuffer in which the sparking-wheel is mounted, an actuating-link pivotally connected with the snuffer, a connecting link pivotally connected with the lower end of the actuating-link, an operating 35 lever, a toggle-link connected with the operating-lever and said connecting link, and a spring bearing upon the lower end of and tending to raise the actuating-lever and move the operating-lever to the normal position.

2. A lighter comprising in combination: a casing, a wick-chamber, a wick in said chamber, a flint-tube outside of said wick-chamber, a flint in the upper end of said flint-tube, a spring on which said flint rests, a sparking-wheel, a snuffer, 40 in which the sparking-wheel is mounted, an actuating-link pivotally connected with the snuffer, a coupling link pivotally connected with the lower end of the actuating-link, an operating-lever, a toggle-coupling link connected with the operating-lever and said link, and a spring bearing upon the lower end of and tending to raise the actuating-link and move the operating-lever to the normal position.

3. A lighter comprising in combination: a cas- 45

ing, a wick, a flint, a sparking-wheel formed with shoulders on one side, a spring positioned to engage with said shoulders, a snuffer in which the sparking-wheel is mounted, an actuating-link 5 pivotally connected with the snuffer, a coupling link pivotally connected with the lower end of the actuating-link, an operating-lever, a toggle-

coupling link connected with the operating-lever and said link, and a spring bearing upon the lower end of and tending to raise the actuating-link lever and move the operating-lever to the normal position.

WILLIAM E. EVANS.
